Primary Examiner — Andrew Kerr*Assistant Examiner* — Chariton Alexakis**CLAIM**

The ornamental design for a camping cookware, as shown and described.

DESCRIPTION

FIG. 1 is a bottom, front, right side perspective view of a camping cookware, showing my new design;
FIG. 2 is bottom, rear, left side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an alternative perspective view of the camping cookware with the its handle of the pot fastened to the lid. The broken lines are shown for the purpose of illustrating parts of the article that form no part of the claimed design.
